UNITED STATES PATENT OFFICE

2,493,082

ELECTRIC MOTOR

Charles Nehrke, New York, N. Y.

Application April 23, 1947, Serial No. 743,360

2 Claims. (Cl. 172—36)

1

This invention relates to improvements in motors, and more particularly does it relate to low voltage and low current electric motors.

An object of this invention is to provide an electric motor of the type described, which may be electrically energized by low voltage and low current dry batteries, such as are commonly used in flashlights.

Another object of this invention resides in the inclusion therein of detachable commutator contact members which are held in frictional contact with the commutator segments of the motor, and which may be readily removed for cleaning or other purposes.

A still further object of this invention is the provision of an organization in which the constituent elements are so arranged structurally and functionally as to assure improved results with materials and members which may be manufactured at reasonable cost, may be easily assembled and which will be efficient in operation with minimum wear to the parts.

This invention possesses other objects and features of advantage some of which, with the foregoing, will be set forth in the following description and in the claims wherein parts will be identified by specific names for convenience, but they are intended to be as generic in their application to similar parts as the art will permit. In the accompanying drawings, there has been illustrated the best embodiment of the invention known to me, but such embodiment is to be regarded as typical only of many possible embodiments, and the invention is not to be limited thereto.

The novel features considered characteristic of my invention are set forth with particularity in the appended claims. The invention itself, however, both as to its organization and its method of operation, together with additional objects and advantages thereof, will best be understood from the following description of a specific embodiment when read in connection with the accompanying drawings, in which:

Figure 1 is an elevational view of the front end of the motor, and shows portions broken away.

Figure 2 is a longitudinal, sectional view of same, taken along the line 2—2 of Figure 1.

Figure 3 is an elevational view of the rear end of the motor, and has portions broken away.

Figure 4 is an end view of the rotor, showing one of the coil windings in section.

Figure 5 is a detail of a part carrying commutator contact members.

Referring in detail to the parts, 11 designates a housing which carries, at its lower end, a perma-

10 nent magnet 12, which, with the housing 11, is held upon a cup-shaped base member 13, by means of the screws 14. The said cup-shaped base member 13, is formed at one end with a short upright element 15, to which is secured, by means of the screws 16, an end plate 17, of suitable insulating material. The opposite end of the said cup-shaped base member 13, is formed with a longer upright element 18, extending upwardly to

15 carry one end of a shaft 19, of a rotor 20. The upright end element 18, is formed with a recess portion 21, within which an oilless bearing 22, is seated and through which the shaft 19, engages. The said bearing 22, is held in place by means of a plate 23, secured to the upright end 20 18, by the screw 24, the said plate 23 having a right angle slotted tongue 25 and being slightly offset as at 26, to form a pocket which holds in place a packing element 27, of felt or other suitable material. A second offset 28, perforated as at 29, is formed upon the plate 23, and is adapted to hold the said oilless bearing 22, in place.

The rear end of the rotor shaft 19, is slightly reduced in diameter to form a bearing 29, which 25 engages through the aforesaid insulator plate 17.

Metallic carrier plates 30, having projecting lips 31 which extend through perforations 32, in the said insulator plate 17, are held upon the said insulator plate and carry frictional contact members 33, which are, in turn, mounted in perforations 34, upon the said carrier plates 30. The said contact members 33, are formed with elongated commutator contact members 35, which frictionally engage commutator segments 36, of the rotor 20. To keep the said commutator contact members 35, normally in engagement with the said commutator segments, there are provided springs 37, the opposite ends of 30 which engage hook projections 38, formed upon the said frictional contact members 33.

The rotor 20, consists of the said shaft 19, to which is securely attached a spider-shaped armature frame 39; and the coils 40, wound upon the said spider, one of which is shown in section 45 (Figure 4), an armature bushing 41, disposed between the shaft 19, and the spider carrying the coils 40; a second bushing 42 termed the commutator bushing, mounted upon the shaft 19 (Figure 2); commutator segments 36, having insulating dividing strips 43; a sleeve 44, of suitable insulating material which engages over the said commutator segments and holds same together; and spacer sleeves 45 and 46, around the said shaft 19, disposed between the oilless bearing 22, and the bushing 41, on one side and the

commutator bushing 42, and the said bushing 41, on the other side respectively. A base block 47, may be provided and secured to the housing 13, by means of screws 48.

Electric conductors (not shown) may be attached to the said projecting lips 31, to supply electric current to the commutator for operating the motor.

I claim:

1. An electric motor comprising a base member, a permanent magnet secured in said base member, an upright bearing element secured to the said base member, a second upwardly extending bearing element secured to the said base member, a rotor having a multiplicity of coils mounted in said upwardly extending bearing elements, a commutator upon said rotor, commutator contact members removably mounted upon one of said bearing elements and means removably attached to said bearing adapted to make connection with an electrical source, the said commutator members being fulcrumed upon

carrier plates removably mounted upon said bearing element.

2. An electric motor as set forth in claim 1, wherein the said commutator contact members are removably mounted and fulcrumed upon said bearing element and are formed with hook projections adapted to engage a spring element to keep the said contact members in frictional contact with the said commutator of the rotor.

CHARLES NEHRKE.
